UNITED STATES PATENT OFFICE

JOHN C. MARSELLUS, OF SYRACUSE, NEW YORK, ASSIGNOR TO JOHN MARSELLUS CASKET COMPANY, OF SYRACUSE, NEW YORK, A CORPORATION OF NEW YORK

SHEET-METAL LINING FOR BURIAL CASKETS

Application filed August 17, 1926. Serial No. 129,699.

This invention relates to burial caskets, commonly known as coffins, of the wooden box-and-lid type as distinguished from the all-metal type, but is equally applicable to the box-sections of caskets of any standard-
5 ized form, size or material.

Large numbers of these caskets of widely varying design and finish are usually carried in stock ready to receive the final draping
10 for prompt delivery to the purchaser upon short notice.

It frequently happens, however, that a purchaser having selected a casket of particular design and finish will require the installation of a sheet metal lining within the box section thereby necessitating the removal of the previously installed upholstering to permit the proper application of the lining to the inner surfaces of the bottom, sides and end of the box after which the upholstering must be replaced within the lining before the casket can be finished ready for use, all of which consumes considerable time and adds materially to the expense of
25 the casket other than the extra cost of the sheet metal lining.

The main object of the present invention is to provide separately portable sheet metal lining of standard forms and sizes according to the interior dimensions and form of the box section of the casket and to equip said lining with the suitable interior upholstering or padding so that if the sheet metal lining is required, it, together with
30 the padding thereon, may be easily and quickly installed within the casket and locked therein against displacement by movable fastening devices.

Another object is to provide the lining with internal cleats of wood to which the upholstering may be tacked without perforating the sheet metal.

Other objects and uses relating to specific parts of the casket will be brought out in
45 the following description.

In the drawings:—

Figure 1 is a top plan of a box section of the casket with my improved lining therein.

Figure 2 is a longitudinal vertical sectional
50 view taken on line 2—2, Figure 1.

Figure 3 is an enlarged transverse vertical sectional view taken on line 3—3, Figure 1.

The box section of the casket may be of any suitable form or size but, as illustrated, comprises a bottom —1—, opposite sides 55 —2— and opposite ends —3—, all of which are made of suitable wood, the bottom section being substantially flat while the side and end portions —2— and —3— preferably flare upwardly and outwardly from the marginal edges of the bottom —1—.

The sheet metal lining is made to conform to the interior contour and dimensions of the outer box section and constitutes what may be termed a supplemental box section 65 having a bottom portion —4—, opposite side portions —5— and opposite end portions —6—, all of which are permanently secured together at their junctions one with the other to form a unitary structure which may be inserted into and removed from the outer box and held in operative position within the outer box section by its own weight aided by its frictional engagement therewith.

If desired, however, this supplemental box 75 section may be additionally held in operative position within the outer box section by movable fastening means such as angular pins —7— which are removably inserted in apertures —8— in the outer section across 80 the upper edges of the supplemental section with their heads in engagement with the inner faces of the adjacent portions of the supplemental section thereby avoiding any necessity for perforating any part of the supplemental section and permitting it to be removed or replaced by simply withdrawing the locking pins —7—, the lining being made of less vertical depth than the interior of the casket for this purpose as shown in Figures 90 2 and 3.

The upper marginal edges of the side and end walls of the supplemental box section or lining are returned inwardly and downwardly to form any inner marginal flange 95 —9— which is relatively narrow vertically and affords a convenient handle or handles by which the supplemental box section may be manipulated into and out of the top of the outer section.

This flange —9— also forms with the adjacent portions of the sides and ends of the lining a marginal groove —9'— for receiving the upper edge of an upholstering or padding —10— which is applied to the interior of the supplemental box section or lining as shown in Figure 3.

After the upper edge of the upholstering has been inserted in the groove —9'— the flange —9— may be pressed outwardly toward adjacent outer walls of the lining to firmly hold this portion of the upholstering or padding in place.

A plurality of angular brackets —11—, preferably of bendable sheet metal are secured at one end by brazing, soldering or equivalent fastening means to the inner surfaces of the side and end portions of the supplemental box or lining relatively short distances from the bottom thereof and have their opposite ends offset inwardly and downwardly to form recesses or grooves for receiving the upper ends of tacking strips —12— of wood or equivalent material to which the lower edges of the upholstering —10— may be tacked without puncturing the sheet metal lining.

These tacking strips extend along the inner faces of the sides and ends of the box lining and preferably rest at their lower edges upon the adjacent portions of the lining bottom —4— while their upper edges extend into the grooves in the brackets —11— and are secured thereto by tacks —13—.

When the brackets —11— are secured to the inner face of the sheet metal lining their lower offset ends are allowed to project inwardly in a more or less horizontal plane to facilitate the insertion of the tacking strips —12— thereunder after which said offset ends are bent downwardly against the inner faces of the upper portions of the wooden strips and tacked thereto to hold said strips in place without puncturing the lining, leaving the lower portions of the strips exposed at the inside of the supplemental box to permit the securing of the lower edges of the upholstering —10— thereto by tacks —13'—, Figure 3.

The lower edges of the lengthwise strips —12— are additionally held in place by cross bars —14— of wood or equivalent material resting upon the bottom of the lining with their opposite ends engaged with the inner faces of the lower portions of the side strips.

These cross bars —14— are arranged in longitudinally spaced relation preferably near the ends of the lining and preferably rest by their own weight upon said bottom without other attaching means so that they may be easily removed or replaced when desired or, if necessary, portions of the upholstering or draping may be tacked thereto without perforating said lining.

This supplemental box lining may be made of zinc, copper or other suitable sheet metal to conform to the interior contour and dimensions of standard forms and sizes of caskets ready for immediate installation in any wooden casket of selected design or finish and, if desired, the upholstering or padding —10— and tacking strips —12— together with the cross bars —14— may be incorporated therein to be installed therewith in a casket of the corresponding interior contour and dimensions.

In either case when the sheet metal lining is required for any casket of selected design or finish it is simply necessary to select a lining of corresponding contour and dimensions with the upholstering, tacking bars and brace bars therein and to place it in the casket box and fasten it in place by the fastening members —7— if required, thus completing the casket ready to receive the selected drapery which may be applied on short notice and secured along its upper edge to the inner faces of the sides and ends of the casket over the upper edge of the lining without perforating said lining.

What I claim is:—

1. A lining for burial caskets comprising an imperforate sheet metal box having its upper marginal edge returned inwardly and downwardly to form a groove open at the bottom to receive the upper edge of upholstering.

2. In a burial casket having an outer box-section, a separately portable sheet metal box-lining conforming to the interior contour and dimensions of the outer casket-box, and wooden tacking-pieces applied to portions of the inner surface of said lining.

3. In a burial casket having an outer box-section, a separately portable sheet metal box-lining conforming to the interior contour and dimensions of the outer casket-box, wooden tacking pieces applied to the inner surfaces of opposite sides of the lining, and braces between said tacking pieces for holding them in place.

4. In a burial casket having an outer box-section, a separately portable sheet metal box-lining, yielding clips secured to the inner surfaces of said lining, and wooden tacking strips held in place by said clips.

5. The combination with a wooden burial casket, of an inner sheet metal box lining seated within said casket, said lining having its upper marginal edge returned inwardly and downwardly to form a marginal groove open at the bottom to receive portions of the upholstering.

6. The combination with a burial casket, of a sheet-metal box-lining fitted within the casket and having its upper marginal edge returned inwardly and downwardly a relatively short distance to form an intervening

groove open at the bottom for receiving parts of the upholstering.

7. The combination with a burial casket, of a sheet-metal box-lining fitted within the casket and having its upper marginal edge provided with an inwardly and downwardly projecting flange, and inner upholstering members having portions thereof inserted from the underside upwardly between the flange and adjacent body portion of the lining, said flange being pressed outwardly toward the adjacent portion of the main body of the lining to firmly hold the intervening portion of the upholstering in operative position.

15 In witness whereof I have hereunto set my hand this 9th day of August, 1926.

JOHN C. MARSELLUS.
